CLAIM

The ornamental design for a pet cage bracket, as shown and described.

DESCRIPTION

FIG. 1 is a front top-right perspective view of a pet cage bracket showing our new design in condition of use with a fan;

FIG. 2 is a front top-right perspective view thereof;

FIG. 3 is a rear top-left perspective view thereof;

FIG. 4 is a rear top-right perspective view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof; and,

FIG. 10 is a bottom plan view thereof.

The broken lines immediately adjacent the shaded areas represent the bounds of the claimed design while all other broken lines are directed to environment; the broken lines form no part of the claimed design.
